UNITED STATES PATENT OFFICE.

GUSTAV REUTHE, OF SAYVILLE, NEW YORK.

CONTROLLING WIRELESS-TELEGRAPH TRANSMITTERS.

1,308,530.

Specification of Letters Patent.

Patented July 1, 1919.

Application filed May 25, 1916. Serial No. 99,793.

To all whom it may concern:

Be it known that I, GUSTAV REUTHE, a subject of the German Emperor, and residing at Sayville, Long Island, New York, have invented certain new and useful Improvements in Controlling Wireless-Telegraph Transmitters, of which the following is a full specification.

My invention is illustrated in the accompanying drawings and its particular novel features are pointed out in the annexed claims.

The present invention refers to means for stabilizing the energy output of a radio transmitter, utilizing frequency changers by which the fundamental frequency of the primary source of alternating current energy is multiplied to obtain the frequency required for radiation.

20 A transmitter of this character is for instance illustrated in the U. S. Patent No. 1,181,556, granted to Von Arco and Meissner, and the present invention in particular constitutes an improvement in the operation 25 of transmitters of this and similar characters.

The novelty of the means concerned in the present invention consists in suitably controlling the electrical characteristics of 30 the several circuits of which such a transmitter arrangement is composed, and so far as these circuits constitute oscillating systems, that they are brought out of resonance to a certain degree with the fundamental 35 frequency of the primary alternating current generator or an integral multiple thereof.

In the accompanying drawing a transmitter arrangement containing such frequency changers is diagrammatically illustrated.

In this diagram 1 is an alternating current generator of a comparatively high fundamental frequency (for instance 8,000 to 45 10,000 cycles per second) which might be suitably driven, for instance by direct coupling with an electromotor 2, as shown in the diagram. The frequency changers I, II, III are arranged in cascade so that for instance each of these elements may double 50 the frequency supplied to it. These frequency changers are indicated diagrammatically merely by a square and may be of any suitable construction known in the art, for 55 instance, in their general construction such as shown in the aforesaid Arco-Meissner

patent. The alternating current is supplied to frequency changer I from the generator 1 and in this circuit connection 4 represents the variable capacity of the generator circuit and 7 the variable inductance thereof. The circuit connections between the three frequency changers I, II, III contain respectively the capacities 5 and 6 and the inductances 8 and 9, all variable. The secondary of the high frequency changer III is connected with the antenna 10 containing the inductance 11. The antenna may be connected to the ground as shown.

It is, of course, obvious to any one skilled 70 in the art that any suitable number of frequency changers may be arranged substantially as shown without departing from the spirit of my invention.

When transmitter arrangements of this 75 character are operated, certain difficulties are encountered in maintaining a steady energy output. At certain frequencies and loads the condition of the whole system becomes unstable. In such condition a very 80 slight variation of operating conditions, such as for instance the variation of the speed of the generator, or of the generator potential, or of the load, is sufficient to vary the current in the generator circuit in leaps 85 so that it becomes very difficult to maintain a steady output, which renders the operation difficult, and even sometimes impossible. Besides, the excess of potential which might result from such leaps is apt to endanger 90 the entire installation. This danger is particularly great in case the entire system is in resonance, that is to say, if the generator circuit is in resonance with the generator frequency and each intermediate circuit in 95 resonance with that multiple of the generator frequency which corresponds to the resulting multiple of the particular frequency 100 changer supplying that intermediate circuit, and also if the antenna at the same time is in resonance with the frequency of the 105 changer which supplies energy to it. In the endeavor to overcome difficulties of this character, it has been suggested before to increase the damping of the intermediate 110 circuits by interposing resistance. While this is indeed adapted to remedy these difficulties, it is done at the expense of the efficiency, because such resistances consume energy.

By careful investigation I have found a means more effective and economical in

avoiding these difficulties, which at the same time avoids the use of resistances and the accompanying needless waste of energy. This means provides that the generator circuit is detuned with the generator frequency, and the intermediate circuits are detuned with the multiple of the generator frequency supplied to them by their particular frequency changer. Especially favorable results are obtained when the tuning means (capacity and inductance) of the generator circuit and of the intermediate circuits are chosen larger than the values corresponding with the exact resonance.

Moreover, very favorable results are obtained in connection with the above mentioned expedient, when the antenna circuit is not exactly in resonance with the multiple of the generator frequency supplied to it. In this case, however, the de-tuning must be such that the constants (capacity and induction) which determine the resonance of the antenna circuit are made smaller than the values corresponding with the resonant condition.

This whole expedient is particularly effective if at the same time the motor which operates the generator furnishing the fundamental frequency is provided with means for varying its energy output for a given speed or generally speaking with means for varying the load characteristic of the motor, so as to prevent the motor from running beyond the speed at which the entire system under given conditions is capable of taking up the maximum energy. If the motor exceeds this critical speed, unstable conditions are established. In other words: these means should be such that they limit the output of the motor at a given speed to a value which is below the maximum energy which the entire system can take up so that if by some reason the revolution number should increase, its output would tend to decrease, *i. e.*, so that the motor can never furnish quite the maximum energy which the electric system is capable of taking up.

In case the generator is driven electrically, as is assumed in the present case, where an electromotor 2 of any suitable construction may be coupled with the generator, the means above referred to for controlling the motor output is well known in the electrical art. For instance, in case of a direct current motor resistance may be placed in the armature circuit, and in case of a single or multiple phase alternating current motor resistance may be placed in the rotor circuits. However, any other suitable means of motor control may also be used.

In the present case it may be assumed for example that the generator 1 is coupled with a three phase alternating current motor 2. This motor is provided with resistances 3

connected to its armature for controlling the output which may be required to meet the given conditions of the transmitter.

In case the generator is driven by steam or water power, such means should be employed for the above purpose as is capable of limiting the output of the driving motor to a speed to suit the given conditions of the system. For instance throttling valves or the like may be used for that purpose. An illustration of such means for controlling the driving motor has been omitted in the present application, inasmuch as they are well known.

The degree of de-tuning against resonance conditions should be determined so that the intended purpose, *i. e.*, the stabilizing of the whole system, is obtained. It is not advisable to carry the de-tuning further, in order to avoid unnecessary decrease in efficiency. The most favorable degree of de-tuning against resonance condition may vary with the different conditions of operation, but anyone skilled in the art can easily find that point at which the system retains a sufficiently high degree of efficiency at a sufficient degree of stability to afford safe and steady operation.

I claim:

1. A radio transmitting system comprising an alternating current generator for generating current at a fundamental frequency, an antenna for radiating energy at a desired integral multiple of the fundamental frequency, a number of frequency-changers and connecting circuits therefor interposed between the generator and the antenna acting to raise the generator frequency to the desired multiple, the circuit containing the generator being detuned against resonance with its own frequency to the point of stability of the system.

2. A radio transmitting system comprising an alternating current generator operating at a fundamental frequency, an antenna for radiating energy at a desired integral multiple of the fundamental frequency, and a plurality of frequency-changers with their connecting circuits interposed between the generator and the antenna for raising the generator frequency to the desired extent, each of the circuits being detuned against resonance with its own frequency to the point of stability of the system.

3. A radio transmitting system comprising an alternating current generator for generating current at fundamental frequency, an antenna for radiating energy at an integral multiple of the fundamental frequency, and a number of frequency-changers and their connecting circuits between the generator and the antenna for raising the generator frequency to the integral multiple desired for the antenna; the circuits connecting the generator and the frequency-changers and

- antenna being detuned, the generator circuit against resonance with the fundamental frequency, and each frequency-changer circuit against resonance to its respective integral 45 multiple of the fundamental frequency.
- 5 4. A radio transmitting system comprising a generator of alternating current at fundamental frequency, an antenna for radiating energy at a desired integral multiple of the 50 fundamental frequency, and a number of frequency-changers and connecting circuits therefor between the generator and the antenna, the circuits including capacity and inductance; the capacity and inductance in 55 the generator circuit being larger than is required to tune the circuit to resonance with the fundamental frequency, and the capacity and inductance of each of the frequency-changer circuits being larger than is required to tune the circuits to resonance with their respective frequencies.
- 10 5. A radio transmitting system comprising a generator of electric currents at fundamental frequency, an antenna for radiating energy at a desired multiple of the fundamental frequency, and a number of frequency-changers and connecting circuits between the generator and the antenna, the 55 circuits containing capacity and inductance; the capacity and inductance of the antenna circuit being smaller than is required to tune the antenna circuit to resonance with its own frequency.
- 15 6. A radio transmitting system comprising a generator of electric currents at fundamental frequency, an antenna radiating energy at a higher frequency, and a number of frequency-changers and connecting circuits between the generator and the antenna, the 60 several circuits containing inductance and capacity; the inductance and capacity of the generator and frequency-changer circuits being larger, and those of the antenna circuit being smaller, than is required to tune the several circuits to resonance with their respective frequencies; in combination with driving means for the generator, provided with means for varying its energy output, the said output being so controlled as to prevent the driving means reaching a speed at which the system absorbs maximum energy.
- 20 7. A radio transmitting system comprising a generator of electric currents at fundamental frequency, an antenna radiating energy at a higher frequency, and one or more frequency-changers and connecting circuits between the generator and the antenna, the 65 several circuits containing inductance and capacity; the inductance and capacity of the generator and frequency-changer circuits being larger, and those of the antenna circuit being smaller, than is required to tune the 70 several circuits to resonance with their respective frequencies; in combination with an electric motor for the generator, provided with means for varying its energy output, the said output being so controlled as to 75 prevent the motor reaching a speed at which the system absorbs maximum energy.
- 25 8. A radio transmitting system comprising a generator of electric currents at fundamental frequency, an antenna radiating energy at a higher frequency, and a number of frequency-changers and connecting circuits between the generator and the antenna, the 80 several circuits containing inductance and capacity; the inductance and capacity of the generator and frequency-changer circuits being larger, and those of the antenna circuit being smaller, than is required to tune the several circuits to resonance with their respective frequencies; in combination with an electric motor for the generator, provided with means for varying its energy output, the said output being so controlled as to prevent the motor reaching a speed at which the system absorbs maximum energy.

GUSTAV REUTHE.
